UNITED STATES PATENT OFFICE.

GEORGE C. TILYOU, OF CONEY ISLAND, NEW YORK.

STAIRWAY.

SPECIFICATION forming part of Letters Patent No. 700,455, dated May 20, 1902.

Application filed September 25, 1901. Serial No. 76,458. (No model.)

To all whom it may concern:

Be it known that I, GEORGE C. TILYOU, a citizen of the United States, residing at Coney Island, in the borough of Brooklyn, city of New York, county of Kings, and State of New York, have invented certain new and useful Improvements in Stairways, of which the following is a specification, reference being had therein to the accompanying drawings.

10 My invention relates to the class of stairways patented to me in and by Letters Patent of the United States of America No. 624,405, dated the 2d day of May, 1899. This stairway comprises two stair-sections suitably supported and means whereby they are simultaneously reciprocated in opposite directions, and is particularly designed to afford amusement to persons using the same, its operation tending greatly to confuse the user. I have 15 found in the actual use of the stairway that as the majority of persons who use it are not familiar with its action it is necessary to guard against possible accident, as at the end of each reciprocation of the stair-sections the top and 20 the bottom steps are raised to a considerable extent above the top and the bottom landing, respectively. This tends not only to give a dangerous appearance to the stairway, but to one who is not familiar with it there is the 25 danger of a misstep, which might result in a fall through stumbling or having the foot crushed between the step and the landing.

30 The object of this invention is to provide a stairway wherefrom these objectionable features will be absent; and to this end the invention consists in certain improvements to the invention shown and described in said Letters Patent No. 624,405, as hereinafter set forth and described, and more particularly 35 pointed out in the claims hereto appended.

Referring to the drawings, Figure 1 is a sectional side elevation of my improved stairway. Fig. 2 is a plan view thereof. Fig. 3 is a detailed plan view of the lower portion of 40 the stairway, and Fig. 4 is a similar view of the upper portion thereof.

Like letters refer to like parts throughout the several views.

Between the landings *a* and *b* are extended 45 the parallel stationary guides or ways *c*, having channels therein to guard against lateral

movement of the reciprocating stair-sections *A* and also carrying antifriction-rollers *d*. The stair-sections *A* each comprise the ordinary stringers *e*, carrying the risers *f* and treads *g*, said stringers seated within the channels in the guides or ways *c* and moving on the rollers *d*. Two of these sections are preferably mounted side by side, the adjoining stringers *e* being fitted snugly together and 55 lubricated to reduce friction, and thus permit the two sections to come into sufficiently-intimate contact to avoid danger of the wearing-apparel being caught between them. It is to be understood that the risers and treads 60 are conterminous and flush with the surfaces of their respective adjoining stringers, so that at least one point of their reciprocation the treads of the two sections will be on the same horizontal plane and form one continuous 65 tread. To the uppermost tread is secured a shield *k* by means of hinges *k'*, the free end of which shield is held by gravity in constant contact with the upper landing *b*. From the lowermost tread is suspended a swinging 70 shield *m* by means of the hinges *m'*. The shield *m* slides in a slot in the lower landing and bears upon and is guided by the roller *n*. The lower landing is beveled away, as shown, 75 to admit of the movement of the shield *m*, due to longitudinal travel of the stair-section, this shield being of sufficient length to remain at all times within the slot in the landing *a*. I also provide a hand-rail *h* on the outer edge of each stair-section *A*, which is 80 carried thereby and reciprocates therewith.

The stair-sections *A* are reciprocated simultaneously and in opposite directions by means of the power-driven double crank-shaft *o* and pitmen *p*.

90 The operation of my improved stairway in so far as has not already been described is as follows: The two parallel stair-sections *A* are rapidly and simultaneously reciprocated in opposite directions by means of the double 95 crank-shaft *o* and pitmen *p*, power being derived from any desired source. This causes the treads to constantly change their position relative to the landings and each other and necessitates considerable agility to mount the 100 first step in either direction and ascend or descend except on one of the sections only.

The continuous movement of the whole section also tends to produce a miscalculation of both height and distance, and there is resulting confusion and amusement. The use of 5 the hand-rail *h*, moving synchronously with its section, serves to prevent accident while on the stairway. The shield *k* at the top landing being hinged to the uppermost tread reciprocates therewith; but the free end 10 drops upon and remains in contact with the landing and maintains constant communication between the stair-section and the said landing, thus presenting at all times a plane surface which prevents a person from stumbling over the projected upper step or from 15 stepping under the tread thereof and having the foot crushed. The swinging shield *m* also reciprocates with its section; but its free end is guided by the slot in the lower landing 20 and passes over the roller *n*, thus maintaining a constant barrier, which prevents a person from inserting the foot beneath the lowermost tread and the landing, with resulting 25 injury to that member. These appliances minimize the danger in the use of my improved stairway and at the same time removes therefrom an appearance of danger, which in actual practice increases the utility of the device.

30 It is not my intention to limit the invention to the precise construction herein shown and described, as it is obvious that there may be many deviations therefrom without departing from the spirit of the invention.

35 Having described my invention, what I claim as new, and desire to have protected by Letters Patent, is—

1. In a stairway, the combination with a re-

ciprocating stair-section, guides or ways therefor, means whereby it is reciprocated and a 40 stair-landing, of a shield in constant communication between said stair-section and said landing, substantially as described.

2. In a stairway, the combination with a reciprocating stair-section, guides or ways therefor, means whereby it is reciprocated and a 45 stair-landing, of a shield hinged to said section and maintained in constant contact with said landing, substantially as described.

3. In a stairway, the combination with a reciprocating stair-section, guides or ways therefor, means whereby it is reciprocated and top 50 and bottom stair-landings, of a shield hinged to the top tread of said stair-section and maintained in constant contact with said top 55 landing and a swinging shield carried by the lowermost tread of said stair-section and moving in a slot in said bottom landing, substantially as described.

4. In a stairway, the combination with a reciprocating stair-section, guides or ways therefor, means whereby it is reciprocated and a 60 top and a bottom stair-landing, of a hand-rail carried by and reciprocating with said stair-section and shields in constant communication between the top and the bottom of said stair-section and the top and the bottom landing respectively, substantially as described.

In witness whereof I have hereunto affixed 70 my signature, this 24th day of September, 1901, in the presence of two witnesses.

GEORGE C. TILYOU.
